CONCRETE BUILDING FORM

J. B. Johnston, deceased, late of Fort Worth, Tex.,
by Ida Mae Johnston, executrix, Fort Worth,
Tex.

Application March 3, 1950, Serial No. 147,552

4 Claims. (Cl. 25—131)

1

This invention relates to concrete building forms in which the opposing spaced walls are comprised of panels joined with each other along their adjacent edges. The panels referred to have found favor in the trade because they are reusable, and because they save time as compared with making and erecting conventional wooden concrete forms.

An object of the invention is to provide a construction and arrangement whereby panels of the described class may be quickly assembled and disassembled.

Another object of the invention is to provide a holding means for the assembled panels whereby little, if any, whaling will be required to resist the lateral forces of the wet concrete against the inner surfaces of the assembled walls.

Generally, the invention is comprised of an arrangement of flat bars detachably secured to the edges of and between the panels, and which bars are arranged perpendicularly to each other and having the end of any one bar located intermediate the ends of an adjacent perpendicular bar.

The invention will be more readily understood by reference to the accompanying drawings and the following description.

Figure 1 is a broken perspective view of a concrete building form in which the opposing walls are made of assembled panels, together with an arrangement of stiffener bars for detachably securing said panels.

Figure 2 is an exploded schematic view of the panel and bar arrangement, and particularly showing the relative positions of the stiffener bars with respect to each other.

Figure 3 is a perspective view of one of the panels and showing the locations of holes in the panel flanges for receiving the pins which project from the stiffener bars.

Figure 4 is a broken elevation illustrating a suggested means for tying the opposing walls of a concrete form when the latter embraces a relatively large area.

In the exemplary form of the invention illustrated in the accompanying drawings, the concrete form, generally designated by the numeral 10, is comprised of opposing spaced walls 11 and 12, formed by separate assemblies of square panels 13 having flanges 14 therearound. When assembling the form 10, the surfaces 15 of the respective panels are positioned opposite each other so as to provide relatively smooth and uniform wall surfaces.

The panels 13 in the respective walls 11 and 55

12 are detachably secured to each other by means of flat stiffener bars 16, each of which is substantially as long as the width of two or more said panels in side-by-side relation. The bars 16 are arranged perpendicular to each other in the manner illustrated in Figure 2 and are provided with projecting pins 17 for engagement in corresponding slip fit holes 18 in all four sides of each panel flange 14. Preferably, each side of each flange 14 is provided with at least two holes 18, and each opposing flat surface of each bar 16 is provided with four projecting removable pins 17 so as to make the adjacent panels rigid with each other. It will be noted in Figure 2 that half bars 19 may be used at the ends of the assembled wall where such bars fit between a perpendicular adjacent bar 16 and the wall end.

When desired, half panels 20 may be installed along the bottom or top of either wall 11 or 12, or may be positioned in the assembled walls 11 and 12 so as to vary the wall heights and widths. Similarly, the half panels 20 may also be employed opposite each other to accommodate window and door opening forms (not shown) when half panel dimensions are desired. Such window or door opening forms are cased in the usual manner for retaining the concrete therearound, and since this practice is conventional, it is not, therefore, shown in detail.

When the walls 11 and 12 are relatively large in area, tie wires 21 may be secured around bars 16 in the opposing walls 11 and 12 and between corners of panels 13.

It will be obvious to those versed in the art that the foregoing panel or stiffener bar arrangement may be quickly assembled by arranging the panels 13 in rows, one upon the other, and with the stiffener bars 16 positioned between the panel flanges 14. The projecting pins 17 are engaged in the openings 18 in the panel flanges 14, and by reason of the truss effect of the respective bars upon adjacent panels 13, the entire walls 11 and 12 will resist the pressure of the concrete poured between the same. However, when the wall areas are relatively large, the described tie wires 21, or similar means, may be employed for resisting such pressure.

The described form of the invention is not restrictive, but may be made in many ways within the scope of the appended claims.

What is claimed is:

1. In a concrete form the combination of panels arranged in horizontal and vertical rows, vertical and horizontal flat stiffener bars detachably secured to and between the edges of adjacent said

panels, said bars being substantially as long as two or more said panel sides, said bars being arranged perpendicularly with respect to each other with the ends of certain of said horizontal bars located intermediate the ends of adjacent said vertical bars.

2. In a concrete building form, panels arranged in horizontal and vertical rows, vertical and horizontal stiffener bars positioned between the edges of adjacent said panels, pins projecting from said bars and received within openings in the edges of said panels, said bars being substantially as long as two or more said panel sides, said bars being arranged perpendicularly with respect to each other with the ends of certain of said horizontal bars being located intermediate the ends of adjacent said vertical bars.

3. In a concrete form, the combination of panels having flanges therearound, said panels being arranged in horizontal and vertical rows, vertical and horizontal flat stiffener bars positioned between said flanges, means detachably securing said bars in their referred to positions, said bars being arranged perpendicularly with respect to each other and with the ends of certain

of said horizontal bars located intermediate the ends of adjacent said vertical bars.

4. In a concrete form, the combination of panels arranged in horizontal and vertical rows, vertical and horizontal flat stiffener bars detachably secured to and between the edges of adjacent said panels, said bars being substantially as long as two or more said panel sides, said bars being arranged perpendicularly with respect to each other with the ends of certain of said vertical bars located intermediate the ends of adjacent said horizontal bars.

IDA MAE JOHNSTON.

Executrix of the last will and testament of J. B. Johnston, deceased.
